UNITED STATES PATENT OFFICE.

CHARLES CARROLL CROSS, OF PHILADELPHIA, PENNSYLVANIA.

NUT AND BOLT LOCK.

1,064,447.

Specification of Letters Patent. Patented June 10, 1913.

Application filed July 18, 1912. Serial No. 710,129.

To all whom it may concern:

Be it known that I, CHARLES C. CROSS, a citizen of the United States of America, residing at the city of Philadelphia, county 5 of Philadelphia, State of Pennsylvania, have invented certain new and useful Improvements in Nut and Bolt Locks, of which the following is a specification.

This invention relates to a nut and bolt 10 lock, and its object is to provide a new and improved device of this nature which shall be effective to hold the nut and bolt in rigid relation when desired, and at the same time be simple to operate and capable of being 15 produced at a small cost.

Described in general terms, the lock consists of an eccentric or cam apertured to fit the nut, and locking means adapted to engage the bolt and connected to the eccentric 20 to be forced thereby into locking engagement with the bolt.

Preferably, the locking means consists of a plate provided with a tapering slot, the edges of the slot having teeth disposed in 25 the direction of the small end of the slot, the plate being provided with a wiper or follower placed opposite the large end of the slot and adapted to engage the eccentric to move the plate and bring the edges of the 30 slot at the small end into engagement with the bolt. Means may also be provided for locking the eccentric to hold the parts in fixed relation.

A nut or bolt lock, constructed in accordance with my invention in its preferred form, is illustrated in the accompanying drawing, in which—

Figure 1 is a top plan of the nut, bolt and lock, assembled, and in locking position. 40 Fig. 2 is a plan of the eccentric. Fig. 3 is a plan of the locking plate. Fig. 4 is a vertical, central section showing the nut and bolt in elevation.

The device, as illustrated, consists of a 45 locking plate 1 and an eccentric or cam 2, the locking plate being provided with a tapering slot 3, the inclined edges 4 of which are provided with teeth 5 disposed toward the small end of the slot, the width of the 50 slot at the large end being greater and at the small end less than the diameter of the bolt 6. At its edge, in alinement with the slot and opposite the large end of the latter, the locking plate 1 is provided with a follower 55 7 to engage the edge of the eccentric 2. This follower, as shown, is formed integral

with the plate and consists of a tongue or extension thereon, bent up at right angles to the plate at 8 and at a distance above the surface of the plate equal to the thickness of the eccentric 2, being turned inward at 9. The top arm 10 of the follower, which is thus turned in, is provided at one side with a projecting member 11 which acts as a latch. This latch is slightly resilient and is bent 60 down to engage radial grooves or notches 12 provided in the eccentric for this purpose, and the eccentric itself is provided with an aperture 13 to fit the particular size and shape of nut 14 to be used so that the eccentric 65 may be passed over the nut, the latter occupying the aperture 13 and in this way connected to the nut whereby the eccentric and nut turn together. In this connection it will be noted that the eccentric is beveled at 70 its top edge at 15 along the portion of its periphery 16 having the least radius. This is done to facilitate the seating of the eccentric and passing under the cam follower 7. 75

In operation the bolt is passed through the member or members to be held, and the locking plate 1 is passed over the projecting end of the bolt, the bolt extending through the slot. The nut is then screwed down on to 80 the plate and turned to a bearing, after which it may be rotated backward a half turn. The eccentric or cam 2 is then passed over the nut, the short radius as at 15 being disposed toward the follower 7. The nut 85 carrying the eccentric is again turned to bearing position. The eccentric, as it rotates, engages with its periphery 16 the follower 7, and as the radius of the portion of the eccentric engaging the follower increases, 90 the plate 1 is forced to one side so that before the follower reaches the greatest radius 95 of the eccentric, the bolt occupies a position near the small end of the slot 3, the teeth 5 being embedded in its cylindrical surface, 100 locking it to the plate 1. At this time the latch 11 engages one of the notches 12 and holds the eccentric against rotation in the reverse direction. Thus, with the locking plate rigidly secured to the bolt by means 105 of the teeth 5, and the eccentric likewise secured to the nut which fits the aperture 13 provided in the eccentric for this purpose, and the eccentric and plate held against relative rotation by the latch 11 and by the 110 increasing diameter of the eccentric, the parts are all held in fixed relation to each

other and the bolt and nut are rigidly connected and relative rotation thereof is prevented.

It will be readily understood that the device is simple in construction, effective in 5 operation, and may be produced by means of an automatic machine at a cost little exceeding that of two washers of the ordinary type.

Having thus described my invention specifically and in detail, I desire to have it understood that the specific terms herein 10 are used in their descriptive rather than in their limiting sense, and the scope of the invention is defined in the claims.

I claim—

1. A nut and bolt lock consisting of a cam apertured to fit the nut, locking means adapted to engage the bolt and connected to the 20 cam to be forced thereby into locking engagement with the bolt.

2. A nut and bolt lock consisting of a cam apertured to fit the nut and rotate therewith, locking means adapted to engage the 25 bolt and connected to the cam to be forced thereby into locking engagement with the bolt, and means for locking the cam against rotation.

3. A nut and bolt lock consisting of a plate 30 having a tapering slot for the bolt, the smaller end of which is of a width less than

the diameter of the bolt, and means rotating with the nut and adapted to engage the plate and force it to one side so that the narrow portion of the slot engages the bolt and 35 locks it.

4. A nut and bolt lock consisting of a cam having an aperture to receive and fit the nut, and a member having a tapering elongated slot to receive the bolt and provided with 40 means opposite the large end of the slot for engaging the edge of the cam to force the slotted member to one side in the direction of the length of the slot and bring the narrow portion of the slot into engagement 45 with the bolt.

5. A nut and bolt lock consisting of a cam having an aperture to receive and fit the nut, and a member having a tapering elongated slot to receive the bolt and provided 50 with means opposite the large end of the slot for engaging the edge of the cam to force the narrow portion of the slot into engagement with the bolt, and means for locking the cam against rotation.

Signed by me at Philadelphia, Pa., this 55
13th day of July, 1912.

CHARLES CARROLL CROSS.
